UNITED STATES PATENT OFFICE.

LEOPOLD MARX, OF BIRMINGHAM, ALABAMA, ASSIGNOR OF ONE-FIFTH TO ROBERT L. GLENN, OF BIRMINGHAM, ALABAMA.

PORTABLE WATER HEATER.

Application filed March 10, 1922. Serial No. 542,720.

To all whom it may concern:

Be it known that I, LEOPOLD MARX, a citizen of the United States of America, residing at Birmingham, in the county of Jefferson and State of Alabama, have invented certain new and useful Improvements in Portable Water Heaters, of which the following is a specification.

This invention relates to an improvement in portable water heaters for boilers suitable for domestic purposes, my object being to provide a simple and inexpensive water heater which will meet the existing demand for such where no running water system or gas mains are available, and which is particularly suitable for use on farms and in mining camps.

A further object of my invention is to provide a novel type of boiler with a series of heating tubes projecting therefrom into a heater suitably attached to the side of the boiler, the heater having suitable means for charging the fuel, dumping the ashes, and removing the same.

My invention further comprises the novel arrangement of a double reservoir provided with means for the supply of cold water from the overhead reservoir to the base of the heater bearing reservoir and with a suitable steam discharge and air vent leading from the latter overhead into the upper reservoir.

My invention also comprises the novel details of construction and arrangements of parts which are hereinafter more particularly described, and which in their preferred embodiment only are illustrated in the accompanying drawings forming part of this specification, and in which:

Figs. 1 and 2 are respectively a side elevation and plan of my water heater and boiler.

Fig. 3 is a sectional elevation of my invention taken on the line 3—3 of Fig. 2.

Fig. 4 is a sectional plan taken on the line 4—4 of Fig. 1.

Fig. 5 is a sectional elevation taken on the line 5—5 of Fig. 1, while

Fig. 6 is the rear elevation of the stove alone showing the location of the holes permitting the insertion of the water tubes.

Similar reference numerals refer to similar parts throughout the drawings.

With reference to Figs. 1 and 2, I show a boiler 1 of any suitable material and capacity supported on a base 2 with outlets 3 and 4 for hot and cold water. A reservoir 5 is supported by the brackets 6 on the boiler 1, said reservoir being open at its upper end to facilitate filling. Leading from the bottom of the reservoir and depending into the boiler 1 within an inch or so of its bottom is a feed pipe 7 which keeps the boiler 1 filled with water as long as the reservoir 5 has any water therein. A vent and overflow pipe 8 is provided for the exhaustion of air in the boiler while filling and for discharging steam and overflow water from the boiler into the tank.

The stove is formed of sheet metal and is made up of the following elements; a body portion 9 provided with a front hopper 10 to receive the fuel. This hopper is covered with a hinged top 11 provided with a simple catch 12 as shown. There is also a smoke outlet and pipe 13 fitted to the top of the body portion 9 of the stove. A grate 14 is hinged to the stove with a latch 15 adapted to hold the grate in normal position. I show an ash box 16 provided with a handle or drawer pull 17, this box being adapted to slide back and forth by means of tongue and groove guides 18 formed on the upper side edges of the box and the lower corresponding lower side edges of the stove. To permit of the easy handling of the ashes, the grate 14 is pivoted at 19 so that upon the release of the latch the grate will fall as indicated in dotted position, Fig. 3, thus dumping the fuel and ashes thereon into the ash box 16. The grate 14 is then lifted back into position by the lever 20 keyed to the grate shaft 19 and latched in its operating position. The rear wall of the stove 9 and box 16 are formed in an arc to conform with the curvature of the boiler 1 and in the rear stove wall are holes 21 which are arranged to register with four water tubes 22 projecting from within the boiler 1, the outer ends 23 of these tubes that enter the stove being closed while the other ends 24 in the boiler are bent upwardly, as shown, and are open, the tubes being soldered or suitably fixed to the side of the boiler. When in operation the projecting closed ends 23 of the tubes 22 are

within and disposed on each side of the stove, and they are surrounded by the fire therein, so as to heat the water in the tubes.

In order that the stove may be held firmly 5 against the side of the boiler yet without permanently affixing same, I provide a metal strap 25 adapted to encircle the boiler and the stove and provided with any suitable tightener means to clamp the stove firmly to the 10 boiler, the weight of the stove being supported by the tubes and this strap.

In order that combustion of the fuel introduced into the stove will take place a series of draft holes 26 are provided in the lower 15 portion of the stove beneath the plane of the grate while same is in normal position.

In operation, water is poured into the tank 5 and runs therefrom through pipe 7 into and fills the boiler up until the latter is entirely 20 full and any desired reserve of water remains in the reservoir 5. The grate 14 is latched in its operating position and the lid 11 is lifted and charcoal or other suitable fuel is introduced into the stove and ignited. 25 The resulting flames encircle the enclosed ends 23 of the tube 22 and rapidly heat the small volume of water contained in each tube. This heated water flows out of the tubes and upwardly towards the top of the boiler 1 and there collects. Should the user desire hot 30 water, the same is drawn from the upper outlet 3, but should he desire cold water or to clean out the boiler he utilizes the lower outlet 4. As the water is drawn from the boiler 35 it is automatically replaced from the reservoir, the vent pipe 8 permitting the water to flow out readily from the otherwise closed boiler 1 and to be replaced by the flow of cold water through pipe 7 into the bottom of 40 the boiler. Should the water become overheated and steam arise, this can readily vent itself through pipe 7, discharging the water ahead of it in pipe 7 into the overhead reservoir, thus making the appliance both automatic and perfectly safe.

In addition to the heating effect of the 50 flames on the tubes, the stove by its extended surface contact with the side of the boiler serves also to rapidly heat the water in the boiler.

Though I have described with great particularity the details of the preferred embodiment of my invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters 60 Patent, is:—

1. A portable water heater comprising a boiler, a fuel burning stove mounted on the side of the boiler, and tubes communicating with the side of the boiler and projecting 65 into the stove, said tubes having their ends within the stove closed and their end within the boiler open and upturned.

2. In a portable water heater, a boiler having a series of tubes opening thereinto 70 and having closed ends which project laterally outwardly from the boiler, and a stove having a side wall provided with apertures arranged to permit said projecting tube ends to pass therethrough into the stove.

3. In a portable water heater, a boiler having a series of tubes opening thereinto which project laterally outwardly from the boiler, a stove having a side wall provided with apertures arranged to receive said projecting tubes, and means to clamp the stove 80 to the side of the boiler.

4. In a portable water heater, a boiler having a series of tubes opening thereinto and having closed ends which project laterally outwardly from the boiler, a stove having a side wall provided with apertures to receive said projecting tube ends, and means to clamp the stove to the boiler, the stove having its face adjacent to the boiler shaped to 90 conform to the boiler contour.

5. In a portable water heater, a boiler having water tubes projecting laterally therefrom, a fuel burning stove having a side wall curved to conform to the boiler and provided with openings to receive said tubes, a strap adapted to surround the boiler and clamp the stove in position on the side of the boiler, and agencies to supply water to and to vent the boiler.

6. In a portable water heater, a boiler having water tubes projecting laterally therefrom with their outer ends closed, a fuel burning stove having a side wall curved to conform to the boiler and provided with openings through which said tubes project, a strap adapted to surround the boiler and clamp the stove in position against the boiler, an auxiliary reservoir mounted on top of the boiler, and pipes respectively connecting the lower and upper ends of the boiler and reservoir.

In testimony whereof I affix my signature.
LEOPOLD MARX.
